Primary Examiner — Marcus Jackson(74) *Attorney, Agent, or Firm* — Fellers, Snider, Blankenship, Bailey & Tippens, P.C.**CLAIM**

The ornamental design for a twin wick top for a torch, as shown and described.

DESCRIPTION

FIG. 1 is front elevational view shown in its environment, the rear elevational view being identical thereto.

FIG. 2 is a front elevational view, the rear elevational view being identical thereto.

FIG. 3 is a top plan view.

FIG. 4 is a right side elevational view, the left side elevational view being identical thereto.

FIG. 5 is a bottom plan view; and,

FIG. 6 is a perspective view.

The broken line showing of the torch is included for the purpose of illustrating only and forms no part of the claimed design.
